UNITED STATES PATENT OFFICE

ARTHUR C. KOOTZ, OF MILWAUKEE, WISCONSIN

MOP CONSTRUCTION

Application filed August 15, 1927. Serial No. 212,933.

The object of the invention is to provide a mop in which the mop material is hung from a wire frame the ends of which may be readily and securely attached to the pivoted connector of the mop handle and permit it to be readily taken off for washing. More particularly, the preferred construction provides a mop in which the handle and the frame have a substantially universal joint connection so that the mop may be used in very restricted places that are not accessible to mops of the ordinary pivoted handle type.

The invention further consists in the several features hereinafter set forth and more particularly defined by claims at the conclusion hereof.

In the drawings, Fig. 1 is a perspective view of a mop embodying the invention, before assembly;

Fig. 2 is a detail view of the assembled mop viewed from within the same, showing one position of the operating handle;

Fig. 3 is a view similar to Fig. 2 showing another view of the operating handle;

Fig. 4 is a detail sectional view taken on the line 4—4 of Fig. 2;

Fig. 5 is a detail view showing a modified form of frame connection.

In the drawings the mop body 6 is shown as of usual construction comprising the mop strands 7 of yarn or other suitable material which are stitched together between layers or strips 8 and 9 of canvas or other suitable fabric, which strips are also secured by the stitching 10 to form a frame-receiving channel or pocket 11.

The frame 12 is formed of relatively heavy wire, preferably of triangular shape, to obtain the advantages well known in this art of getting into corners or other restricted spaces, and extends through the pocket 11 and the ends 13 of said frame extend inwardly from its rear side and in each instance are disposed substantially parallel to each other and permit the mop body to be readily strung or worked over them so as to dispose the frame within the pocket 11 with the free ends 13 projecting inwardly.

In each instance the handle 14 of the mop

securely clamped thereto by a bolt 17 passing through the spaced ears of said portion and said connector is provided with spaced apertured bifurcations 18.

In each instance means are provided for clamping the ends of the frame 12 firmly together and for securing the bifurcations 18 in pivotal connection therewith.

In Figs. 1 to 3, inclusive, this means includes a pivot and clamping bolt 19 having a wing-nut 20 and a channeled metal connector 21.

This connector 21 is formed of sheet metal bent to provide a pair of channels or recesses 22, each adapted to receive one of the free ends of the frame and the bolt 19 passes through the apertures in the bifurcations 18 and the upstanding legs of the connector 21, two of which are centrally disposed and one at each end abutting the adjacent bifurcation 18 so that when the nut 20 is drawn up the ends of the frame are tightly clamped between adjacent legs of the connector 21 and the bifurcations are also frictionally held to the connector so that the handle will readily retain its adjusted position relative to the frame.

With this construction the handle may be adjusted vertically to any desired inclination relative to the frame and I have also found that the frame permits the handle to be tilted laterally, as shown in Fig. 3, owing to the flexing of the free ends of the frame so that the height of the handle above the mop body may be decreased to permit the use of the mop in confined places.

In Fig. 5 the means for clamping the ends of the frame firmly together and for securing the bifurcations 18 in pivotal connection therewith comprises a channel connector member 23 between which and the pivot bolt 24 the free ends of the frame are disposed and clamped by the nut 25 and said bolt passing through said connector 23 and the arms or bifurcations 18 and a washer 26, it being noted that in this instance the free ends of the mop frame are arranged in vertical alignment in the connector while in Fig. 2 the free ends are arranged in horizontal alignment, and that in both instances a free

end of the frame is clamped between a portion of the connector and the pivot bolt.

I desire it to be understood that this invention is not to be limited to any particular form or arrangement of parts except in so far as such limitations are specified in the claims.

What I claim as my invention is:

1. In a mop, the combination with a mop body having a frame-receiving pocket, of a frame extending through said pocket and having its free ends extending inwardly of its periphery, a frame connector comprising a sheet metal member bent to provide adjacently disposed yielding channel members providing pockets receiving the free ends of said frame, a handle connector, and a pivot bolt extending through said handle connector and the inner and outer sides of said channel members above said pockets and applying pressure to draw the sides of said channel members together to clamp the ends of the frame thereto.

2. In a mop, the combination with a mop body having a frame-receiving pocket, of a mop frame extending through said pocket and having its free ends extending inwardly of its periphery, a pivot bolt, a metal frame-clamping connector having yielding portions engaging the free ends of said frame and confining them between said connector and the pivot bolt, and a handle connector, said pivot bolt securing said connectors together and extending through both connectors and applying pressure to said yielding portions of said frame-clamping connector to draw them together to clamp the ends of the mop frame thereto.

3. In a mop, the combination with a mop body having a frame-receiving pocket, of a frame extending through said pocket and having its free ends extending inwardly of its periphery, a channeled frame connector having yielding portions engaging the free ends of the frame, a handle connector, and a pivot bolt clamping said connectors together and clamping said ends between the yielding portions of said frame connector.

In testimony whereof, I affix my signature.

ARTHUR C. KOOTZ.
